METHOD AND APPARATUS FOR DESURFACING FERROUS METAL BODIES

James Harold Bucknam, Cranford, N. J., assignor to The Linde Air Products Company, New York, N. Y., a corporation of Ohio

Application October 24, 1936, Serial No. 107,373

5 Claims.

(CL. 148—9)

This invention relates to a method and apparatus for desurfacing ferrous metal bodies, and more particularly, to a method and apparatus for conserving the shape and heat of the relatively large reaction puddle which is formed thermo-chemically when desurfacing with a gang of nozzles applying oxidizing gas on a hot surface of a ferrous metal body.

The invention has for its object generally the provision of an improved procedure and steps in a method of the character set forth, together with suitable apparatus for carrying the same into effect, whereby improved operating characteristics and effects are had.

15 A specific object of the invention is to provide a procedure for assisting the surface tension of the reaction puddle to act in a manner tending to effect the desired conservation and to retain the reaction puddle intact in a central position with respect to the gang of nozzles on the body being desurfaced.

Another object is to provide means for applying an external component of force in a manner which supplements the normal cohesive forces operating in the surface of the reaction puddle so as to give a resultant which assists in retaining the puddle as a unitary mass and to prevent its sloughing off at the sides.

Another object is to provide an optimum range 30 for the angular orientations taught in the U. S. Patent to E. A. Doyle, No. 2,125,179, issued July 26, 1938, for the oxygen impinging nozzles about axes perpendicular to the surface being removed.

Still another object of the invention is to provide an arrangement of nozzles for multiple nozzle desurfacing adapted to give components of force which tend to urge the reaction puddle to a central position and maintain it there ahead of the reaction zone.

40 Other objects of the invention will in part be obvious and will in part appear hereinafter.

The invention accordingly comprises the several steps and the relation of one or more of such steps with respect to each of the others, and the apparatus embodying features of construction, combinations of elements and arrangements of parts which are adapted to effect such steps, all as exemplified in the following detailed disclosure, and the scope of the invention will be indicated in the 50 claims.

For a fuller understanding of the nature and objects of the invention reference should be had to the following detailed description taken in connection with the accompanying drawing, in 55 which:

Fig. 1 is a side elevation showing an arrangement for multiple nozzle desurfacing of a billet when the top surface is being removed in accordance with the invention;

60 Fig. 2 is a top plan view of the nozzle arrange-

ment used in connection with the illustration in Fig. 1 and depicts the mutual inclination of the oxidizing gas streams employed in the practice of the invention; and

Fig. 3 shows a modified arrangement of the 5 nozzles where the number is different from that shown in Fig. 2.

In the art of desurfacing ferrous metal bodies with oxidizing gas, it is now common practice to remove the surface of ingots, billets, and the like, to a desired relatively shallow depth in comparatively wide cuts, by impinging a plurality of relatively voluminous side-by-side streams of oxidizing gas upon a region of surface extending transversely to the direction in which a cut is to be taken, and at acute angles to a plane which is tangent to the surface at the points of impingement; the application of gas being in the general direction of the metal removal. The oxidizing gas employed may be either commercially pure oxygen or a mixture of oxygen and a neutral gas; the nozzle exit velocity with which the gas is supplied is preferably of a relatively low value. A suitable velocity of this character has as its 10 upper limit the acoustic velocity and may have a 15 value taken within the general range of from 200 to 1000 ft. per second, as set forth in the U. S. Patent to Oldham, No. 1,957,351.

The surface removed by the thermo-chemical reaction of the oxidizing gas impinged upon the 20 surface of the ferrous metal body must be initially raised to the temperature at which the oxygen will react, i. e., to the oxygen ignition temperature, in order that the thermo-chemical reaction may 25 take place. The elevating of the surface to such ignition temperature may be accomplished by the application of a suitable preheating gas flame to the surface at a period of time and in a position somewhat ahead of the time and region at which the oxidizing gas is applied. A mixture of oxygen and acetylene is suitable as the heating gas 30 mixture to be supplied in the practice of the present invention. Where the ingot or billet is to be desurfaced while hot, as a step in a steel mill manufacturing process, it may be unnecessary to 35 practice the preheating of the surface to the ignition temperature since the uncooled billet is frequently at or above such ignition temperature.

When the reaction is started, a puddle or fused 40 mass of slag which may contain molten iron forms on the surface just ahead of the region impinged by the oxidizing gas. For multiple nozzle desurfacing, the nozzles are usually so closely spaced that the several reaction puddles coalesce, and a single puddle results that moves 45 over the surface as the desurfacing nozzles and the metal body are removed relatively. While the puddle thus formed is a relatively viscous mass and has a relatively high surface tension, it has been found in practice that the puddle has 50

a tendency to spread laterally, i. e., transversely and in a direction parallel to the region upon which the oxidizing gas is impinged. As a result, there is a continual sloughing off of the slag at the sides and a consequent loss of the heat that is contained in the material so lost. The puddle as a rule has a substantial portion in contact over a considerable area of the metal body ahead of the gas applying nozzles, and hence imparts conductively a relatively large amount of heat to the surface to be removed. The puddle thus assists in attaining the desired preheating effect on the surface metal in advance of the cut.

In the practice of the present invention a step is taken for supplementing the effect of the surface tension in the reaction puddle in a transverse direction so as to minimize the tendency of sloughing off at the sides and thereby accomplish a conservation of the heat of the puddle. This conservation also makes for greater uniformity in depth of the cut which is made.

In order to carry out this step, an arrangement of nozzles is employed which imparts the desired assistance to the surface tension as a supplemental external force, such force being derived from the velocity of the gas applied. To this end, a plurality of nozzles are oriented toward each other through small angles about axes substantially perpendicular to the plane tangent to the surface being removed so as to apply transverse velocity components to the surface of the puddle. Where more than two nozzles are employed, this is seen to involve the inclining of each pair of nozzles on opposite sides of a center line mutually toward each other. In this manner, the normal cohesive forces of surface tension in the reaction puddle are supplemented externally so that the puddle is retained as a unitary mass moving ahead of the reaction zone.

Referring now to the drawing, and particularly to Fig. 1, B denotes a fragmentary portion of a billet whose top surface is being thermo-chemically removed by a gang of nozzles 10 arranged in accordance with the invention. These nozzles 45 may be of any suitable type, for example, of the conventional type having cylindrical bores, as now commonly used in the art. Here, the nozzles 10 have connections 11 for supplying both oxidizing gas and heating gas to the nozzle passages 50 after traversing a head 12 which may be water-cooled, if desired (water-cooling connections being omitted from the drawings in the interests of clearness of illustration). The oxidizing gas is shown as a stream 13 impinging upon the top surface 55 face of the billet B, and making an acute angle in a vertical plane of about 25 degrees with its trace in the tangent plane, the stream 13 being surrounded by a plurality of small heating gas jets 14. The region of the surface impinged by 60 the several streams of oxidizing gas is the region or zone where the thermo-chemical reaction takes place and "burns off", as it were, the surface metal to be removed to a desired depth, for example, to an average depth of $\frac{1}{8}$ inch. A puddle 65 of slag, as indicated at P, forms ahead of the impinged gas in the reaction zone and has a billows-like crest R which moves ahead of the portion more immediately adjacent the reaction zone.

In Fig. 2, an arrangement of nozzles is shown 70 whereby external components of force are applied to the surface of the puddle P to assist in its retention centrally on the billet being desurfaced. Here, an even number of oxidizing gas supplying nozzles are depicted and denoted respectively 10^a, 75 10^b, 10^c, and 10^d. The two inside nozzles 10^b and

10^c are seen to be mutually inclined toward the center line x-x of the billet at small angles, which may have values, for example, of from 5 to 15 degrees. The outside nozzles 10^a and 10^d are also mutually inclined, but at increasingly greater angles than the inner nozzles, since in this way the supplemental components of force may be made to have comparatively large values at the edge of the puddle. In practice, the nozzles 10^a and 10^d may be inclined at angles of from 10 to 20 degrees. Any suitable mechanical spacing means, for example, a toothed bar as shown at 15, may be employed for retaining the nozzles properly spaced and in the desired mutually inclined positions.

To make a desurfacing cut with the arrangement shown in Figs. 1 and 2, preheating gas flames are first applied to the place where the cut is to start. When this place is at the oxygen ignition temperature, the oxidizing gas streams 20 are turned on. After this, the billet and the heads carrying the oxidizing gas applying nozzles are moved relatively at a suitable speed, for example, at 60 ft. per minute. The oxidizing gas thereby impinged upon the surface is applied not 25 only at an acute angle to the tangent plane of the billet's surface at the place of impingement but is inclined somewhat laterally through angles having axes substantially perpendicular to the tangent plane so as to give lateral components of 30 force that are applied to the surface of the reaction puddle and supplement the normal cohesive forces operating in the surface of the puddle producing resultants which tend to have equilibrium only along the center line of the billet 35 but increase in value as the edge of the puddle is approached. As a consequence, these forces tend to retain the puddle as an imperforate unitary fused mass moving centrally ahead of the reaction zone with little liability to substantial 40 losses through sloughing off at the sides.

In Fig. 3, an arrangement of nozzles employing an odd number is shown. Five nozzles are depicted and are denoted respectively 10^a, 10^b, 10^c, 10^d, and 10^e. Here, it is seen that the central 45 nozzle 10^e is not oriented through any angle about a vertical axis but has its projection parallel to the center line x'-x' of the billet. The two inside nozzles 10^b and 10^c are mutually inclined toward the center line through small angles as 50 were the nozzles 10^b and 10^c in Fig. 2, while the two outside nozzles 10^a and 10^d are oriented through somewhat greater angles. Thus, it is seen that external components of force, increasing with the approach to the outer edges of the 55 reaction puddle, are provided, which operate to retain the reaction puddle centrally as an imperforate unitary fused mass moving ahead of the reaction zone when a desurfacing cut is being taken.

Since certain changes in carrying out the above process and in the constructions set forth, which embody the invention may be made without departing from its scope, it is intended that all matter contained in the above description or 60 shown in the accompanying drawing shall be interpreted as illustrative and not in a limiting sense.

Having described my invention, what I claim as new and desire to secure by Letters Patent is:

1. The process of thermo-chemically desurfacing a ferrous metal body which comprises impinging a plurality of oxidizing gas streams upon a region extending across a surface of said body when at the oxygen ignition temperature, said streams 75

being applied through nozzles arranged to supply gas in relatively large volumes at acute angle to a plane tangent to the surface being removed in the region of impingement and in the general direction of advance of the desurfacing reaction, inclining said streams mutually toward each other by orientations through angles of from five to twenty degrees about axes substantially perpendicular to said tangent plane, said orientation having a direction and magnitude such as to derive an external component of force supplementing the normal cohesive forces which operate in the surface of the reaction puddle that forms in the region impinged by said oxidizing gas streams to an extent which causes the reaction puddle to move centrally ahead of the reaction zone with little liability to sloughing off at the sides, and imparting relative motion to said plurality of oxidizing gas streams and said metal body.

2. The process of thermo-chemically desurfacing a ferrous metal body which comprises applying heating gas flames to the surface to be removed to raise the temperature of the same to the oxygen ignition temperature, impinging a plurality of oxidizing gas streams upon a region extending across a surface of said body when at the oxygen ignition temperature, said streams being applied through nozzles arranged to supply gas in relatively large volumes at acute angles to a plane tangent to the surface being removed in the region of impingement and in the general direction of the desurfacing reaction, inclining the streams of oxidizing gas on each side of a center line mutually toward each other by orientations through angles about axes substantially perpendicular to said tangent plane, said orientations adjacent said center line being relatively small and of a value from five to fifteen degrees and having a direction such as to derive an external component of force supplementing the normal cohesive forces which operate in the surfaces of the reaction puddle that forms in the region impinged by said oxidizing gas streams, said orientations for the streams outside of those immediately adjacent said center line being from ten to twenty degrees and progressively increased whereby the transverse components of force tend to move the reaction puddle to the center of the reaction zone, there being a region of equilibrium along the center line, and imparting relative motion of said plurality of oxidizing gas streams and said metal body.

3. Apparatus for thermo-chemically desurfacing a ferrous metal body comprising, in combination, means for supporting a body in a position to be operated upon, a group of heads movably supported above said supporting means, each of said heads having a nozzle for impinging a relatively voluminous stream of oxidizing gas upon a surface to be removed of a metal body when on said supporting means, said streams being impinged at acute angles to a plane tangent to the surface being removed in the region of impingement and in the general direction in which a desurfacing reaction takes place, means for holding said heads in positions such that the streams of oxidizing gas are mutually inclined toward each other on opposite sides of a center line, said inclinations being through angles of from five to twenty degrees about axes substantially perpendicular to said tangent plane, said angles being selected to have directions and magnitudes

which derive external components of force from the velocity of said gas streams and supplement the normal cohesive forces operating in the surface of the reaction puddle that forms in the region impinged by said oxidizing gas streams, and means for moving said group of heads relatively to said supporting means.

4. Apparatus for thermo-chemically desurfacing a ferrous metal body comprising, in combination, means for supporting a body in a position to be operated upon, a group consisting of an even number of heads operatively disposed with respect to said supporting means, each of said heads having a nozzle for impinging a relatively voluminous stream of oxidizing gas upon a surface to be removed of a metal body when on said supporting means, said streams being impinged at acute angles to a plane tangent to the surface being removed in the region of impingement and in the general direction in which a desurfacing reaction takes place, means for holding a pair of heads on opposite sides of a center line mutually inclined toward each other through angles about axes substantially perpendicular to said tangent plane, said angles having a magnitude of from 5 to 15 degrees and directions such as to give external components of force derived from the velocity of said gas streams which supplement the normal cohesive forces operating in the surface of the reaction puddle that forms in the region impinged by said oxidizing gas streams, a pair of nozzles which are outside of said first-named pair and on opposite sides of said center line being mutually inclined toward each other through angles of slightly greater magnitude than said first-named angles, and means for moving said group of heads relatively to said supporting means.

5. Apparatus for thermo-chemically desurfacing a ferrous metal body comprising, in combination, means for supporting a body in a position to be operated upon, a group consisting of an odd number of heads operatively disposed with respect to said supporting means, each of said heads having a nozzle for impinging a relatively voluminous stream of oxidizing gas upon a surface to be removed of a metal body when on said supporting means, said streams impinging at acute angles to a plane tangent to the surface being removed in the region of impingement and in the direction in which a desurfacing reaction takes place, means for holding the central head in said group in a position such that the projection of the stream of oxidizing gas impinged on the surface to be removed is parallel to the center line of said group, the pair of heads adjacent said central head being inclined toward each other through angles whose axes are substantially perpendicular to said tangent plane, said angles having a magnitude of from 5 to 15 degrees and a direction such as to give a component of force derived from the velocity of said gas streams operating inwardly toward said center line, the pair of heads next adjacent said first-named pair of heads being inwardly inclined through angles about axes substantially perpendicular to said tangent plane and having magnitudes of from 10 to 20 degrees and directions such as to give external components of force directed toward said center line, and means for moving said group of heads relatively to said supporting means.

JAMES HAROLD BUCKNAM.

CERTIFICATE OF CORRECTION.

atent No. 2,157,095.

May 9, 1939.

JAMES HAROLD BUCKNAM.

It is hereby certified that error appears in the printed specification of the above numbered patent requiring correction as follows: Page 2, first column, line 54, for "impigning" read impinging; line 65-66, for "impigned" read impinged; same page, second column, line 43, for the word "add" read dd; page 3, first column, line 2, claim 1, for "angle" read angles; line 9, for "haid" read said; and that the said Letters Patent should be read with this correction therein that the same may conform to the record of the case in the Patent Office.

Signed and sealed this 13th day of June, A. D. 1939.

Henry Van Arsdale
